UNITED STATES PATENT OFFICE.

ALEXANDER HOLMES, OF EUREKA, CALIFORNIA.

WINDOW-SHADE AND ROLLER ADJUSTMENT.

No. 815,294.

Specification of Letters Patent.

Patented March 13, 1906.

Application filed February 14, 1905. Serial No. 245,565.

To all whom it may concern:

Be it known that I, ALEXANDER HOLMES, a citizen of the United States, residing at Eureka, in the county of Humboldt and State 5 of California, have invented new and useful Improvements in Window-Shade and Roller Adjustment, of which the following is a specification.

My invention relates to improvements in 10 the adjustment of shade-rollers with relation to the windows upon which they are used.

It comprises details of construction which will be more fully explained by reference to the accompanying drawings, in which—

15 Figure 1 is a front elevation. Fig. 2 is a side. Fig. 3 is a top view. Fig. 4 is an enlarged view of the roller, showing the central telescope-shaft. Fig. 5 is a reduced sectional view of the left-hand portion of the 20 roller of Fig. 4.

It is the object of my invention to provide an accurate and effective means for adjusting and holding shade-rollers at any desired point with relation to the light-openings of 25 windows and the like, so that any proportion of the light may be admitted or cut off between the bottom and top of the window and either above or below the shade.

A represents a window frame or casing, 30 and 2 represents toothed racks fixed to the casing in any desired manner. As hereshown, the rack or toothed portions are fixed flat upon each side of the window-opening and are upturned or angular in shape, having upon 35 the outer portion inturned flanges, as at 3.

4 represents the shade-roller, made of any suitable or desired construction, but a satisfactory form will be the usual shade-rollers containing spiral springs and having a pawl- 40 and-ratchet mechanism by which the shade may be rolled or unrolled and maintained at any point. Through the shade-roller is a supporting journal-shaft. This shaft may be made in two sections, a hollow portion 5 45 entering the shade-roller at one end and a corresponding portion 6, either solid or hollow, entering the opposite end of the shade-roller and having such size as to telescope within the part 5. The two parts 5 and 6 50 are made with feathers or corresponding groove and key, so that while they are slideable longitudinally they will not turn with relation to each other. These portions extend outwardly from the shade-roller, and upon 55 the ends are fixed the toothed wheels 7. These wheels are adjusted so as to engage

the teeth of the racks 2, and it will be seen that by the telescopic arrangement of the internal rods they may be separated or brought together so as to fit any width of window or 60 light-opening to which they are to be applied. The shade will be coiled upon the central portion of the roller which is devoted to it and may be rolled or unrolled upon the two bearing-rods without reference to the position in which these parts are held. The ends of the shafts upon which the wheels 7 are 65 fixed extend out beneath the flanges 3, and the toothed wheels are thus maintained in mesh with the racks, the shafts turning and 70 sliding beneath the flanges 3 whenever they are moved up or down.

8 is a rod connected with one end of the shade-roller shafts, and, as here shown, it is bent to clasp the shaft which can also turn 75 freely within it. The rod is carried in close to the window-frame and is then bent so as to extend parallel with the frame to a point within convenient reach of an operator. This rod has teeth or notches formed in it, as 80 shown at 9, and these are engaged by a spring 10, which is fixed with such relation to the rod that this point will bear with elastic pressure against the rod, and when the rod is moved up or down the roller-shaft will be 85 pushed in unison with the movements of the rod. As the toothed wheels are fixed upon each end of the roller-shaft, it will be seen that the revolution of one upon its rack will cause the other to move simultaneously, and 90 thus the shade-roller will be maintained substantially straight across the window. If the shade is to be raised so that its upper edge is close to the top of the window, it is only necessary to push upward upon the rod 95 8, and the yielding of the spring will allow the notches in the rod to pass freely. If the shade is to be pulled down, the spring may be either turned to one side to disengage from the rod or it may be slightly lifted, so that 100 the rod can be pulled down, and the toothed wheels turning in the racks, as before described, will bring the shade-roller down to any desired point. Thus it may be fixed at a point between the bottom and top of the 105 window, and if the shade be pulled to the bottom the light will all pass in over the top of the roller and shade. If moved to a point nearer to the top and the shade partially raised from the bottom, light may be admitted both at top and bottom. Thus a 110 single roller will control the admission of

light through the window and take the place of double shades, which may be journaled both at top and bottom of the window.

Having thus described my invention, what I claim, and desire to secure by Letters Patent, is—

1. A window-shade attachment having in combination a shade-roller, a shaft extending therethrough and having toothed wheels at the ends, racks upon the window-casing engaged by said wheels said racks having flanges by which the wheels are maintained in contact therewith, and said roller comprising telescopic members whereby it is adjustable for different widths of light-openings, a rod having one end bent to clasp the shaft and to allow the latter to turn freely within it, ratchet-teeth on the rod and a spring-pressed pawl adapted to engage the

ratchet-teeth and thereby hold the roller in its adjusted position.

2. In a shade-roller adjustment, a roller-shaft having toothed wheels fixed upon its ends to turn in unison, parallel racks with which the teeth engage, a guided slideable bar with notches formed upon it, and with the upper end of which the wheel-shaft is turnably connected, and a spring-pressed pawl engaging the notches of the bar and holding it and the roller at any point of adjustment. 30

In testimony whereof I have hereunto set my hand in presence of two subscribing witnesses.

ALEXANDER HOLMES.
